AUTOMOBILE DOORLATCH

Walter C. Merideth and Oran A. Sidwell,
Denver, Colo.

Application November 13, 1934, Serial No. 752,805

8 Claims. (Cl. 70—29)

This invention relates to an automobile door latch. With some types of automobile door latches, an auto thief can, by means of a wrench or other tool, twist the door handle until the lock is broken and released. Various locks and latches have been designed which, when locked, release the exterior handle. This allows the latter handle to be freely rotated so that an auto thief can not obtain access by twisting a handle. Such locks, and latches, however, have been objectionable, for when released, the handle may project at any angle which detracts from the appearance of the automobile, and requires a manual adjustment of the misplaced handle when the lock is unlocked or the latch is released.

The principal object of this invention is to provide an automobile latch which, when locked, will allow the handle to be freely turned without damage to the lock, yet will automatically return the free handle to its proper aligned position when the latch or lock is released.

Other objects are to provide a cheap, simple, rigid construction for the latch members; and efficient construction for releasing the exterior handle when the latch is locked from the inside; and a construction which can not be damaged by unauthorized tampering.

Other objects and advantages reside in the detail construction of the invention, which is designed for simplicity, economy, and efficiency. These will become more apparent from the following description.

In the following detailed description of the invention, reference is had to the accompanying drawings which form a part hereof. Like numerals refer to like parts in all views of the drawings and throughout the description.

In the drawings:—

Fig. 1 is a horizontal section through the latch case, taken on the line 1—1, Fig. 2.

Fig. 2 is a vertical section illustrating the latch in the unlocked or released position. This section is taken on the line 2—2, Fig. 1.

Fig. 3 is a similar section illustrating the latch in the locked position.

Fig. 4 is a view of the inner face of the lock case, partially broken away to show the interior construction.

Fig. 5 is a longitudinal section through the external handle shaft, illustrating it adapted to a key lock.

Fig. 6 is a similar section, taken on the line 6—6, Fig. 5.

Fig. 7 is a detail face view of the pinion (15) of Fig. 5.

The latch may be designed to suit any desired installation, and may, if desired, be provided with any of the usual cylinder lock mechanisms. As illustrated in Figs. 1, 2, and 3, the key mechanism has been omitted. A method of installing a key operated mechanism is illustrated in Figs. 5, 6, and 7, and will be later described.

The latch illustrated in Figs. 1, 2, and 3 is for locking doors of an automobile from the interior of the car without the use of a key.

The mechanism is installed in a suitable latch case 9. An inner handle shaft 10 terminating in an inside handle 11; and an outer handle shaft 12, terminating in an outside handle 13 project from opposite faces of the case. A locking bolt 14 projects from one extremity thereof.

The outer handle shaft 12 is journaled in the front face of the case 9, and in an offset plate 59 secured to the rear face of the case 9 by means of suitable rivets 60. A spur pinion 15 is secured on the shaft 12 immediately in front of the offset plate 59. The pinion 15 meshes with a rack member 16 carrying suitable rack teeth 17 along one of its edges. The rack member 16 is suspended from a bell crank lever 18 mounted on a suitable hinge pin 19. The bell crank lever 18 is pivoted on a pivot pin 20 from the rear face of the case 9. The other extremity of the bell crank lever 18 carries a crank pin 21 which rides in a notch 22 in the bolt 14.

It can be readily seen that if the shaft 12 is rotated in a clockwise direction (Fig. 2) the spur pinion 15 will travel in the rack teeth 17 to pull the rack member 16 downwardly, causing it to actuate the bell crank lever 18. This causes the crank pin 21 to engage the extremity of the notch 22 to pull the latch bolt 14 inwardly, as shown by the broken line positions in Fig. 2. Thus, operation of the outside handle 13 will withdraw the bolt 14. The bolt 14 is returned to its original position when the handle 13 is released by a coil spring 23, the extremity of which engages a projecting shoulder 24 on the latch bolt 14.

The handle shaft 10 is journaled in the rear face of the case 9, and is secured at its inner extremity to a locking plate 25. The handle is preferably formed with a square extremity 26 so that it will not rotate in the plate 25. The upper extremity of the plate 25 carries a link pin 27. The rearward extremity of the latch bolt 14 carries a similar link pin 28. An open link 29 extends between the link pins 27 and 28.

It can be seen that if the shaft 10 is rotated in a clockwise direction (Fig. 2) it will pull the latch bolt 14 inwardly to the broken line position through the medium of the link pins 27 and 28, and the link 29. Thus the latch bolt 14 can be actuated by movement of the inside handle 11. Actuation in this manner, however, does not move the outside handle 13. This is due to the fact that the notch 22 is of sufficient length to allow the latch bolt to move inwardly without engaging the hinge pin 21.

We have now described the normal operating functions of the handles 11 and 13 upon the latch bolt 14. Means are provided whereby operation of the inside handle 11 in the opposite direction, or counterclockwise in Fig. 2, will release the outside handle 13 so that it cannot be used to operate the latch bolt 14.

This is accomplished through the medium of the locking plate 25 which is extended downwardly a sufficient distance to be brought into engagement with a ratchet notch 30 formed in a swinging lever 31. The swinging lever 31 is hingedly secured to the rear wall of the case 9 at 32. The lower extremity of the swinging lever 31 is connected through the medium of a connecting rod 33, with a second bell crank lever or triangular plate 34, through the medium of suitable hinge pins 35 and 36.

The triangular plate is pivoted to the rear face of the case 9 on a pivot pin 37. The side extremity of the triangular plate carries a link pin 38 which travels in a vertical slot 39 in the rack member 16. The swinging lever 31 is constantly maintained against the plate 25 by means of a spiral spring 40.

Now, if it is desired to disengage the exterior handle 13 so that the latch can not be operated from the exterior of the car, it is only necessary to swing the inside handle 11 upwardly. This causes the lower corner of the plate 25 to force the swinging lever 31 rearwardly until the corner engages in the notch 30, as shown in Fig. 3. This action has swung the triangular plate 34 so that the link pin 38 has traveled upwardly in the slot 39 and has swung the rack member 16 out of engagement with the pinion 15. The outside handle 13 can now be freely rotated but will have no effect whatsoever on unlocking or withdrawing the latch bolt 14.

It is desirable to provide some means for returning the outside handle 13 to the horizontal or natural position when it is released. This is accomplished by means of a spring actuated lever 41, which is pivoted at 42 to the rear of the case 9, and is connected with a tension spring 43 at its lower extremity. The lever 41 connects with a connecting rod 44 which extends to short crank member 45 secured on the inner extremity 60 of the external shaft 12 inside the offset plate 59.

Naturally the pull of the spring 43 causes the connecting rod 44 to continuously return to its extreme "left" position on the crank member 45 whenever the exterior handle 13 is released. Rotation of the exterior handle causes the crank member 45 to swing the lever 41, and increase the tension in the spring 43. Thus, it can be readily seen that the outside handle will always remain in the horizontal position unless acted upon by an external force, and will always return to the horizontal position when the external force is released.

The above construction allows either handle to operate the latch bolt, when desired, without actuating the other handle; it allows the outside

handle to be disconnected from the latch bolt, by operation of the inside handle, so that the outside handle cannot operate the latch; and it causes the released handle to maintain its proper aligned position at all times.

To assist in bringing and holding the released handle 13 to alignment, a leaf spring 46 may be employed. This spring bears against a flat face 47 on the pinion 15. Any rotation of the handle shaft 12 causes the extremities of this flat face 10 to press against and bend this spring 46. The spring, of course, resists this bending and in so doing swings the handle 13 back to its normal position when it is released.

In Figs. 5, 6, and 7, a method of applying a key actuated lock to the external handle 13 is illustrated.

In this form of the invention, the handle shaft comprises: a tube 48, to the outer extremity of which the handle 13 is attached. A lock cylinder 49 is rotatably mounted in the tube 48, the rotation of which is controlled by any suitably designed pin tumblers 50 actuated by means of a suitable key 51. The lock cylinder 49 is internally threaded to receive a threaded stud 52 which is connected to a spline 53. The extremity of the spline 53 fits into depressions 54 formed in the pinion 15. The pinion is mounted upon a shaft 55 which passes freely therethrough, terminating in the crank member 45 to which the connecting link 44 is connected. The shaft 55 is bifurcated so as to pass on each side of the spline 53.

When the key 51 is turned in one direction, it will thread the stud 52 outwardly so as to force the spline 53 into the notches 54 in the pinion 15. This locks the pinion to the cylinder 49, so that movement of the handle 13 will be communicated directly to the pinion. When the key is turned in the other direction, the threaded connection 40 between the stud 52 and the cylinder 49 will withdraw the spline 53 from contact with the pinion 15 so that rotation of the tube 48 will not rotate the gear 15.

It will be noted that the connecting link 44 is always connected through the shaft 55 to the tube 48 so that it will act to always return the tube and its handle 13 to the normal position, regardless of whether the lock is locked or unlocked. It also acts to return the spline 53 to alignment with its notches 54 so that it may immediately return when the lock is unlocked. The spline 53 is formed with projecting ears 57 which travel in slots 58 in the shell 48, so as to prevent rotation of the spline and threaded stud therein.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:—

1. A door latch mechanism comprising: a latch case; a first handle shaft projecting from one side of said latch case; a second handle shaft projecting from the other side of said latch case; a bolt projecting from one extremity of said latch case; a lever secured on the inner extremity of said first handle shaft; a pinion on the inner extremity of said second handle shaft; a rack member engaging said pinion and operatively connected to said bolt so that movement of said pinion in one direction will draw said bolt into said case; and movement in the other direction

will not affect said bolt; means for withdrawing said rack member from contact with said pinion when desired, said latter means comprising: a swinging lever adapted to be contacted by the lever on said first handle shaft; and a connecting rod extending from said swinging lever to an operable connection with said rack bar.

5. A door latch mechanism comprising: a latch case; a first handle shaft projecting from one side of said latch case; a second handle shaft projecting from the other side of said latch case a bolt projecting from one extremity of said latch case; a lever secured on the inner extremity of said first handle shaft; a pinion on the inner extremity of said second handle shaft; a rack member engaging said pinion and operatively connected to said bolt so that movement of said pinion in one direction will draw said bolt into said case; and movement in the other direction 10 will not affect said bolt; means for withdrawing said rack member from contact with said pinion when desired, said latter means comprising: a swinging lever adapted to be contacted by the lever on said first handle shaft; and a connecting rod extending from said swinging lever to an operable connection with said rack bar, said connecting rod extending from said swinging lever.

15. A door latch mechanism comprising: a latch case; a latch bolt projecting from one extremity of said case; a spring urging said latch bolt to the projected position; a handle shaft projecting into said latch case; a pinion secured on said handle shaft; a rack member meshing with said pinion; a bell crank lever swingingly supporting said rack member at its one extremity; a pin carried by the other extremity of said lever, said pin traveling in an elongated notch in said bolt so as to allow inward movement of said bolt 20 without actuation of said bell crank lever; and means for withdrawing said rack from contact with said pinion when desired.

25. A door latch mechanism comprising: a latch case; a latch bolt projecting from one extremity of said case; a spring urging said latch bolt to the projected position; a handle shaft projecting into said latch case; a pinion secured on said handle shaft; a rack member meshing with said pinion; a bell crank lever supporting said rack member at its one extremity; a pin carried by the other extremity of said lever, said pin traveling in an elongated notch in said bolt so as to allow 30 inward movement of said bolt without actuation

of said bell crank lever; means for withdrawing said rack from contact with said pinion when desired; and a spring actuated member eccentrically mounted on said handle shaft so as to return the latter to its original position when 5 released.

3. In a door latch mechanism having a handle shaft and means for releasing the handle shaft from the latch mechanism when desired, means for turning the released shaft to a predetermined position of rotation comprising: a push rod eccentrically connected to said handle shaft at its one extremity; and a spring exerting a constant push on said rod so as to cause it to turn said shaft to its normal position when it is 10 released the connection of said push rod with said handle shaft being such that said shaft may be rotated entirely around in either direction.

4. In a door latch mechanism having a handle shaft and means for releasing the handle shaft from the latch mechanism when desired so that it may be completely revolved, means for turning the released shaft to a predetermined position of rotation; and resilient means for releasably 20 holding said shaft in said position.

5. In an automobile door latch mechanism; a latch bolt; a handle shaft; a pinion on said handle shaft; a vertically movable rack; a bell crank lever translating the vertical movement of 25 said rack into horizontal movement of said bolt; a second handle shaft; a projecting plate on said second shaft; a swinging lever adapted to be contacted by said plate; and a connecting bar transmitting the movement of said swinging lever to 30 said rack so as to swing it out of engagement with said pinion when said second handle shaft is turned in one direction.

6. In an automobile door latch mechanism: a latch bolt; a handle shaft; a pinion on said handle shaft; a vertically movable rack; a bell crank lever translating the vertical movement of 35 said rack into horizontal movement of said bolt; a second handle shaft; a projecting plate on said second shaft; a swinging lever adapted to be contacted by said plate; a connecting bar transmitting the movement of said swinging lever to 40 said rack so as to swing it out of engagement with said pinion when said second handle shaft is turned in one direction; and means for locking 45 said second handle shaft in the latter position.

WALTER C. MERIDETH.
